Attorneys.

UNITED STATES PATENT OFFICE.

HERMAN HEUSER, OF EVANSTON, ILLINOIS.

VACUUM-DISCHARGE APPARATUS.

1,388,565.

Specification of Letters Patent. Patented Aug. 23, 1921.

Application filed November 21, 1919. Serial No. 339,772.

To all whom it may concern:

Be it known that I, HERMAN HEUSER, a citizen of the United States, residing at 929 Sheridan road, Evanston, in the county of Cook and State of Illinois, have invented a new and useful Improvement in Vacuum-Discharge Apparatus, of which the following is a specification.

The present invention relates to vacuum discharge apparatus, and more particularly to apparatus intended to effect the discharge of liquid from a system such as an evaporating or dealcoholizing system, wherein a vacuum is maintained.

15 In order that the invention may be clearly understood, a specific embodiment thereof is shown in the drawing, in which the figure shows an elevation of an apparatus constructed in accordance with the invention.

20 Referring more particularly to the drawing the numeral 5 indicates the discharge line from a vacuum apparatus, for example, the condenser of an evaporating or dealcoholizing system. By a suitable angular fitting 6, the discharge line is connected to the intake 7 of a wet vacuum pump 8 of any suitable type, shown in end elevation. The vacuum pump 8 discharges through pipe 9 and the downwardly extending pipe 10 into the 25 funnel shaped top 11 of the pipe 12 leading to any suitable collecting means. The top of the funnel shaped opening 11 is covered with a screen 13 to permit the free escape of the air or gas accompanying the discharge liquid.

The discharge pipe 5 is provided with a liquid gage 14, the upper end of which is connected to the discharge pipe at a point 15 above the intake of the vacuum pump. The 40 lower end of the gage 14 is connected to the pipe 5 by means of a fitting 16 at a point below the intake of the vacuum pump. The

fitting 16 may be also provided with a try-cock 17.

The liquid gage 14 is thus so located that 45 the level of the liquid on the intake side of the wet vacuum pump can be readily observed. In the actual operation of the apparatus, it is essential to the successful functioning of the vacuum apparatus to which 50 the pump is attached, and to the maintenance of a vacuum therein, that the liquid level in the discharge pipe shall not rise above the level of the intake of the pump except momentarily. If this should occur, the 55 pump would draw liquid only and the efficiency of the vacuum apparatus would be seriously impaired. Furthermore, when a liquid seal is permitted to form and to rise in a condenser pipe from a vacuum dealcoholizer, as illustrated, in the present case, an increase in pressure in the evaporating system is caused. This is particularly the case when cooling is effected in the condenser by the direct contact of the evaporated vapors 60 with the cooling medium. By means of the gage 14 the liquid level may be observed and the proper control applied to maintain it at 65 a point below the top of the intake pipe 7.

Although the present invention has been 70 described in connection with certain details of apparatus, it is clearly understood that these details are not intended to be regarded as limitations upon the scope of the invention, except in so far as included in the accompanying claim.

I claim:

In combination, a discharge line, a vacuum pump, the intake of which is directly connected to the discharge line and a liquid gage 80 connected to said discharge line at points above and below the intake of the vacuum pump.

HERMAN HEUSER
